RAILWAY COUPLER CONTROL SYSTEM

Otto E. De Haven, La Monte, Mo.

Application February 29, 1932, Serial No. 595,745

20 Claims. (Cl. 213—212)

The present invention relates to coupler operating means for railway trains, and aims to provide an improved coupler control system by which the operation of uncoupling of cars can 5 be conveniently and effectively controlled by the engine crew, without necessitating the presence of any operator at any time at the points of connection between the cars.

Accordingly, I have devised an improved system of control connections arranged for electric operation throughout the train and having control switches at a central point, as in the engine cab if preferred, and adapted to carry out the coupling or uncoupling action at any point along 15 the train, that is, between any two cars of the train. The system further comprises suitable signaling and indicator means whereby the operator may be advised of each successive step taking place, both as to the coupling and uncoupling action, and also as to the relative position of 20 each car in the train.

It is further sought to provide a system of this character which may be installed with a minimum of expense or change in the present type of 25 railway equipment, and adapted to utilize the air supply of the brake system as the operating medium for effecting the operation both of the coupling and uncoupling actions, as well as the indicator means.

It is a still further object of the invention to 30 devise a remote control system of the aforesaid character which will also offer no interference with the manual control of the couplers in the usual manner where such operation should be found necessary.

The invention further comprises improvements 35 in the form of air hose connections which are provided between the cars which will enable them to be effectively connected in either end-to-end relation.

With the foregoing general objects in view, the invention will now be described by reference to the accompanying drawings illustrating one practical and efficient form of embodiment of the proposed control system, after which those features and combinations deemed to be novel will be set forth and claimed.

In the drawings—

Figure 1 is a diagrammatic view illustrating 50 the operating elements of the electric circuit connections in relation to the front and rear couplers of one car of a train equipped with the present system (together with the control switches and indicating and signaling means therefor);

Figure 2 is an end elevation of a car showing

the relative positions of the several contact elements whereby the electric circuits are made or broken through adjoining cars, together with the relative position of the air hose connections;

Figure 3 is a diagrammatic elevation showing a portion of a train with different operative positions of the circuit connecting elements indicated in full and dotted lines, respectively;

Figure 3A is an enlarged detail of the connections between cars A and B of Figure 3 and Figures 4 and 5 are enlarged details of the three-way type of valve hereinafter referred to.

Referring now to the drawings in detail, and more particularly to Figure 1, this shows a complete unit of the coupler control as applied to one 15 car of a train, the air brake service line 10 of which is connected by way of a check valve 11 to an air storage tank 12 for supplying the actuating medium for the coupler operation and also for actuating certain circuit-making contacts as hereinafter described. Accordingly, a pipe 14 connects the tank 12 with a cylinder 15 provided with a piston 16 and rod 17 terminating in a fork 18 for engagement with the crank 19 connected with the coupler pin 20 of what may 25 be termed the "rear" coupler 21 of the car. A three-way valve 22 is located in the pipe 14 in advance of the cylinder 15 and provided with an operating arm 23 in position for actuation by an electromagnet or relay coil 24 in an electric circuit 30 30, whereby air may be admitted to the cylinder for actuating the piston in opposition to a spring 26. When the coil of said electromagnet is deenergized, the valve 22 is automatically operated by a coil spring 28 to shut off the air 35 from the tank 12 and exhaust the air from the cylinder 15, and hence permit automatic retraction of the piston rod 17 by the action of the spring 26, in an obvious manner.

A similar set of connections with equivalent 40 parts, all indicated by primed numerals, is provided for what may be termed the "front" coupler 21' of the car.

To the tank 12 is also connected a pipe 30 communicating with a cylinder 32 midway between 45 the ends of the cylinder, in which cylinder operate a pair of oppositely moving pistons 33 connected with piston rods 34 projecting slidably through the frame members 35 at the opposite ends of the car, each rod being provided with a 50 collar 36 and coil spring 37 operating to hold the rods normally in retracted position, with the pistons 33 in similarly retracted position within the cylinder 32. Each rod 34 also carries a pin 38 in sliding engagement with the forked end of a 55

lever 40 having its opposite forked end in sliding engagement with the pin 41 on the inner end of a rod 42 operating slidably through the frame 35 at the corresponding end of the car. The outer ends of the rods 42 carry contact plates 44 which are connected by an electric circuit wire 45, and the outer ends of the rods 34 are similarly provided with contact plates 46 connected by an electric circuit wire 47 having a branch conductor 48 leading to a grounded electromagnet or relay coil 49 arranged to operate the arm 50 of a three-way valve 51 (similar to the valves 22 and 22') which controls the flow of air through the pipe 30 (see Figure 4) and is maintained by a spring 52 in position for closing communication with the tank 12 with the cylinder 32 open to the outside air, until the arm 50 is actuated by said electromagnet for operating the valve for the purpose of opening up communication between the tank 12 and cylinder 32, as hereinafter more particularly explained.

When the arm 50 is actuated by the relay 49 to open the valve 51, it is automatically latched by a detent 54 operated by a spring 55, which detent 25 is adapted to be retracted, for unlatching said valve arm, by the action of a grounded electromagnet or relay 56 having an electric circuit connection 57 with the contact plates 44 at the front end of the car.

30 The wire 47 is also connected with a wire 60 having two branches 61 connected to a pair of contacts 64 and 65 provided with switch elements 62 and 63 respectively in the circuit leading to the relay coil 24. Each of said switches 62, 63, 35 is provided with a spring 66 adapted to hold the switch in open position until engaged by a finger 67 on the corresponding piston rod 34, whereby the switch is closed and maintained closed during the retracted position of the rod as illustrated in Figure 1. Each of the piston rods 34 also carries 40 a finger 68 adapted to be brought by the opposite movements of the rods into engagement with either of a pair of grounded switches 69 and 70, each of which is held in circuit-open position by 45 means of a coil spring 71; whereby operation of the switches by said finger 68 moves them into momentary engagement with contacts 72 and 73 in the respective branches 74 and 75 of an indicator circuit wire 76 tapped to an electric feed 50 wire 77 which connects two contact plates 78 at opposite ends of the car. Each of these contact plates 78 is carried by a plunger rod 79 suitably actuated by a spring 80 into position for maintaining constant engagement of the contact plates 55 between each pair of cars that are in coupled relation.

The finger 68 carried by the piston rod 34 corresponding to the "front" end of the car is also adapted, on initial contacting engagement of its contact plate 46 with that of the adjoining car 60 of the train, to make grounding contact with a contact element or switch 82 in a branch wire 83 tapped onto the feed wire 77, for producing a signal as hereinafter explained.

65 The signal mechanism and control switch connections, to be positioned at a single remote point of operation, such as in the engine cab, will now be explained. A suitable source of electric current supply is provided, such as a battery 85,
70 suitably grounded and having its other terminal provided with a conductor 86 having one branch 87 provided with a pair of electromagnets or relays 88 and 89, and connecting with the contact plate 78 of the engine or its tender; another branch 90 provided with a switch 91 connecting

with the contact plate 44 of the engine or tender; and a third branch 92 provided with a set of switches 93, 94 and 95, arranged in parallel and connecting with the contact plate 46 of the engine or tender. The electromagnets or relays 88-89 are for the purpose of controlling a pair of valves 96 and 97 respectively, which are connected with an air supply pipe 98 (which may be connected with the air brake line) communicating with a cylinder 100 containing a piston 101 carried by a piston rod 102, the outer end of which is operatively connected with an index arm 103, the pointer of which moves around a graduated dial 104 numbered for the purpose of designating consecutive numbers corresponding to the number of cars in the train. Each valve is provided with an operating arm 105 and spring 106 for returning the arm to initial position when released by its electromagnet, the operation of the valve 97 admitting an impulse of air to the cylinder 100, while the momentary opening of the valve 96 (which is of a three-way type similar to the valve 51) exhausts an equivalent amount of air from the cylinder (see Figure 5), thereby permitting retraction of the piston and piston rod 102 therein by the action of a coil spring 107, and thus producing the opposite movements of the index arm as required for registering the successive operations of said valves.

A suitable exhaust or bleeder valve 115 may be used to exhaust the air from the cylinder 100 when necessary for initial adjustment or setting the indicator arm 103.

Provision is made for the operation of the valve 97 in response solely to closing movements of either of the switches 69, and for similarly confining the operation of the valve 95 to the closing of either of the switches 70. For this purpose, I use marginal current relays 88 and 89 which are relatively slow and quick acting, i. e., with relatively high and low resistance windings, respectively, and adapted to operate on a corresponding difference in current values, as determined by the resistances 108 and 109 in the respective switch circuits. To illustrate, with the relay 88 designed to operate on a current of one-half to one ampere in a half-second of time, and relay 89 designed to operate on a current of not less than one ampere in less than a half-second of time, it will be seen that for a current of one ampere or greater the relay 89 will operate before the relay 88 has had time to operate; whereas, for a smaller current than one ampere the relay 88 will operate but the relay 89 will not. Moreover, whenever the relay 89 does operate, the coil 88 may be cut out by causing said operation to open the contacts in the circuit as indicated at 105'. A signal light 110 (with a suitable circuit-closing relay 110') is also included in the circuit branch 88 as shown, which light will therefore flash in response to the closing of any one of the switches referred to. It will thus be seen that whenever the contact plate 46 at the front end of the car is engaged by the contact plate 46 of an adjoining car (due to the outward operative movement of the piston rod carrying the latter plate 46) the initial result of such movement will be a movement of the finger 68 sufficient to engage the switch 82 and produce a flash of the light 110, indicating that the front end of the car was receiving said contacting engagement. Thereafter any operation of the arm 50 for either opening or closing the valve 51 will obviously produce corresponding operation of the switches 69 and 70 in response to the move- 75

ment of the piston rods 34 in either direction, for not only flashing said signal light but also energizing the corresponding magnets or relays 88 and 89, and thus registering the successive 5 engagements and disengagements of the contact plates 46.

In this connection it may be explained that 10 operation of the electromagnet or relay 49 in any case is only effected by maintaining the switch 93 closed, while operation of the electromagnets or relays 24 and 24' may be selectively effected by closing of the switches 94 and 95 respectively, while the switch 93 is open, for which purpose the relays 24 and 24' are of the same type and 15 arrangement, i. e., relatively quick and slow acting, respectively, as the relays 89-88, and adapted to operate on relatively different current values as determined by resistances 99 and 99' connected with the said switches 94 and 95 respectively. 20 Thus with suitably chosen current values the relay 24 will operate before the relay 24' has had time to operate, and the relay 24' will operate on a current insufficient to operate relay 24; and whenever the quick acting relay 24 does 25 operate, the current may be shunted around the coil 24' by causing said operation to close contacts in a shunt circuit as indicated at 23'. Inasmuch as relay 49 is required to operate prior to and without operating either of the relays 30 24-24', said relay 49 is of a still quicker acting type and designed to operate on a still smaller current value as may be determined by a suitably high resistance 99'' associated with its control switch 93.

35 The range of movement of the rods 34 carrying the contact plates 46 is such that a projected plate 46 will engage and move rearwardly an opposed retracted plate 46 so that the corresponding finger 68 will engage and operate the 40 corresponding switch 82.

A spring buffer 112 is carried by the front piston rod 34 between the cylinder 32 and a collar 114 also carried by said rod, and all these parts are so proportioned and arranged that the 45 reaction of the spring 112 will disengage the finger 68 from the switch 82 after only momentary contact hence preventing any further flashing of the light 110 prior to the operation of the switch 69.

50 As already indicated, each car of a train provided with the foregoing equipment will carry a set of the connections illustrated in Figure 1 with the exception that the indicating and signaling instruments and control switches will be 55 located at the point of remote control, as at the engine, since normally the engine crew will be in charge of the system. As an illustration of the operation of the system, the following will serve as a typical example, reference being had to Figures 1, 3 and 3A.

One requirement not already mentioned is that 60 all three contact plates or elements 44, 46 and 78 of that end of the first car which was coupled to the engine will be in constant contacting engagement with those carried by the engine, as represented at the right end of Figure 3; while 65 throughout the rest of the train the contact plates 78 between each two coupled cars will be in continuous contact for the purpose of maintaining an uninterrupted electric indicator circuit 70 throughout the train, whereas the other pairs of contact plates 44 and 46 are intermittently engaged in consequence of the operation of the switches 91 and 93 according to the requirements of the various steps of the uncoupling 75

operation, as carried out by operation of the switches 94 and 95, as will be explained hereinafter.

It will be seen that the purpose of the contacts 44 and circuit connections 45 is to provide 5 a continuous coupler control circuit throughout the train for enabling the switch operator, by proper further operation of the switch 93, to select a particular pair of switches 62-63 corresponding to the couplers to be operated, which 10 is done by closing the switch 93 long enough to effect the opening of all other switches 62-63 in advance of that particular pair of said switches (that is all other switches 62-63 between that point and the engine), thus establishing the 15 requisite circuit conditions for operation of either switch 94 or switch 95 according to which end of the car is to undergo the uncoupling operation.

Referring now to Figures 3 and 3A, it will be 20 assumed that one of the train of cars represented, say the car G is to be "spotted", or cut from the train for the purpose of switching it onto a side track. The operator will first close the switch 91 for reasons above stated, in order to form a 25 complete circuit through the contact plates 44 and circuit wires 45; for the train might have been previously left with some of the contact elements 46 closed, in which case the closing of the switch 93 would not register such cars on 30 the indicator dial 104, and hence the necessity of reestablishing the circuit through all the contacts 44 in order to make sure that every car will register properly each time its circuit 45 is 35 broken at the contacts 44 (as well as, vice versa, when said circuit is re-made on reengagement of 40 said contacts, as the operator closes the switch 91). Since all circuits are always closed between the car A and the engine E, the closing of switch 91 energizes the electromagnet 56, which releases 45 the detent 54 in case the latter is engaged with the valve lever 50, thereby releasing the pressure from the cylinder 32, so that the piston rods 34 will be subjected to the action of the springs 37.

While the carrier for the engine contact 46 will 50 maintain it and the contact 46 of car A closed, the operation just described will result in the separation of the contacts 46 between the cars A and B, as shown by the dotted lines in Figure 3A, and simultaneously the finger 68 will close the 55 indicator switch 70, energizing the electromagnet 88, and opening the valve 96 which allows retraction of the indicator one point on the dial 104; the closing of this circuit also flashes the signal lamp 110.

This same operation will take place throughout the train, bringing the indicator 103 around to zero on the dial 104, and it will be noted that this retraction of the piston rods 34 has resulted in not only the engagement of all contacts 44 in 60 the circuit 45, but has also closed all the coupler circuit switches 62 and 63 on all the cars. Consequently, the next step is to establish a direct circuit from the switches 94-95 to the car G which is to be uncoupled, first from the car H 65 and thereafter from the car F. This is accomplished by reestablishing the circuit 47 through the contacts 46 of the successive cars, beginning with the car A and stopping as soon as car G is reached and before opening the valve 51 in said 70 car G. This is accomplished in detail as follows: As soon as the switch 93 is closed (it being remembered that the contacts 46 are always engaged between car A and the engine E), the electromagnet 49 of car A is energized and caused to 75

open the valve 51 to admit pressure to the cylinder 32, which actuates the pistons and causes engagement of the contacts 46 and the separation of the contacts 44 between cars A and B, as indicated by the full lines in Figure 3A. At the same time the rearwardly moving finger 68 momentarily closes the switch 69 and produces both a flash of the signal light and also opening movement of the valve 97 for actuating the indicator 103 one point on the dial; also if the "front" end of car B is coupled to car A (that is, with the switch or contact 82 in front of the cylinder 32 of car B), then the impact due to the engagement of the contacts 46 between cars A and B will have caused the finger 68 to close the contact momentarily through the wire 83, and produced a signal flash at 110, indicating that the front end of car B is coupled to car A.

The switch 93 is held closed until "6" is reached on the dial, indicating that the contacts 46 of cars F and G (assuming that five cars have already been indicated on the dial) are now engaged, and if there is a second flash of the lamp 110 in addition to that following the engagement of said contacts 46 of cars F and G, it will also indicate that the front end of car G is coupled to car F. This serves to inform the operator that by at once opening the switch 93 (to prevent operation of the electromagnet 49 and valve 51 of car G, so that the switches 62-63 of its coupler circuits will remain closed), he may now operate the switch 94 to close the circuit through the electromagnet 24 and thereby uncouple car G from car H. In the event such uncoupling action should fail for any reason, it is then possible for the operator to close the switch 93 again until car H is included in the coupler circuit 47, and the flashing of the signal light noted to determine which end of car H is coupled to car G, and then the proper switch 94 or 95 operated to uncouple car H from car G.

With the cars G and H thus uncoupled, by means of one or the other of the operations just described, the engine can now run the section 45 of the train with car G at its end for the purpose of "spotting" it on the side track. Since the foregoing operation has left all the coupler circuits on these cars open, due to the open position of the switches 62-63, the uncoupling of car 50 G cannot be effected until said circuits are again closed. This is accomplished during the interval while in transit to the "spotting" position, by the same operation of switches 91 and 93 already described, that is, dialing back to zero while switch 91 is closed, then opening switch 93 until the number "5" for car F registers on the dial 55 and then uncoupling it from car G; or, continuing to dial to "6" for car G, and then uncoupling it from car F.

Essentially the same procedure is followed for the purpose of effecting any other uncoupling operation which may be desired between any two of the cars of the train.

While there has been illustrated and described 65 one suitable and practical form of embodiment of the proposed system of connections and operating means therefor, it is apparent that the arrangement shown is susceptible of many variations or modifications, all within the spirit and scope of my invention, and I desire therefore to reserve the right to make whatever changes may be deemed fairly to fall within the scope of the following claims.

Having thus described my invention, what I 75

claim to be new and desire to secure by Letters Patent is:

1. A train coupler system comprising a signal and indicator circuit including separable circuit-connecting elements in engagement at the coupled ends of adjoining cars, a car coupler control circuit provided with remote switch control connections and separable circuit-connecting elements in engagement at said coupled ends of the cars, and means responsive to operations of said second circuit for simultaneously actuating the first circuit to successively indicate the cars affected by said operations.

2. A train coupler system comprising a signal and indicator circuit including separable circuit-connecting elements in engagement at the coupled ends of adjoining cars, a car coupler control circuit provided with remote switch control connections and separable circuit connecting elements in engagement at said coupled ends of the cars, both sets of said connecting elements being arranged to permit contacting engagement thereof in either end-to-end relation of the several cars, and means responsive to operation of said second circuit for simultaneously actuating the first circuit for producing an indicating signal and successively registering the order of the cars as affected by said operation.

3. A train coupler system comprising coupler operating mechanisms for controlling the relation of the couplers between adjoining cars of the train, an electric circuit provided with remote switch control connections and electromagnetic means for operating the coupler mechanism of each of said cars, remote control means for selectively confining the operation of said first circuit to the coupler mechanism of a single car of the train, and a signal and indicating circuit responsive to said control operations for registering the number of cars in advance of the 40 car to which the action of said coupler operating mechanism is being confined.

4. A train coupler system comprising coupler operating mechanisms for controlling the relation of the couplers between adjoining cars of the 45 train, an electric circuit provided with remote switch control connections and electromagnetic means for operating the coupler mechanism of each of said cars, and remote control means for selectively confining the operation of said first 50 circuit to the coupler mechanism of a single car of the train, said first circuit including means for selectively actuating the coupler connections at either end of each car of the train.

5. A train coupler system comprising coupler 55 operating mechanisms for controlling the relation of the couplers between adjoining cars of the train, an electric circuit provided with remote switch control connections and electromagnetic means for operating the coupler mechanism of each of said cars, and remote control means for successively breaking the coupler control circuit in the several cars from said remote control point to a given car of the train.

6. A train coupler system comprising coupler 65 operating mechanisms for controlling the relation of the couplers between adjoining cars of the train, an electric circuit provided with remote switch control connections and branch circuits on each car having electromagnetic means for 70 operating the coupler mechanism thereof, a switch in each branch circuit for opening and closing the same, remote control means operative for successively closing the said branch circuit switches throughout the train, and a re- 75

remote control connection operative to effect the successive opening of said switches from said remote control point to a given car of the train.

7. A train coupler system comprising coupler operating mechanisms for controlling the relation of the couplers between adjoining cars of the train, an electric circuit provided with remote switch control connection and branch circuits on each car having electromagnetic means for operating the coupler mechanism thereof, a pair of switches in each branch circuit for opening and closing the same with reference to the front and rear couplers, respectively, remote control means operative for successively closing said branch circuit switches throughout the train and thereafter successively opening the same from said remote control point to a given car of the train, and means for selectively actuating the coupler connections at either end of said given car while the branch circuit switches thereof remain closed.

8. A train coupler system comprising coupler operating mechanisms for controlling the relation of the couplers between adjoining cars of the train, an electric circuit provided with remote switch control connection and branch circuits on each car having electromagnetic means for operating the coupler mechanism thereof, a pair of switches in each branch circuit for opening and closing the same with reference to the front and rear couplers, respectively, remote control means operative for successively closing said branch circuit switches throughout the train and thereafter successively opening the same from said remote control point to a given car of the train, a signal responsive to the operation of said remote control means for indicating one of the relative end-to-end positions of said given car, and means for selectively actuating the coupler connections at either end of said given car wherein in said branch circuit switches are allowed to remain closed.

9. A train coupler system comprising an indicator circuit including separable circuit-connecting elements in engagement at the coupled ends of adjoining cars and also a fluid-pressure operated indicator device adapted to be actuated from the air brake line of the train, a car coupler control circuit provided with remote switch control connections and separable circuit-connecting elements in engagement at said coupled ends of the cars, and means responsive to operations of said second circuit for simultaneously actuating the first circuit to successively indicate the cars affected by said operations.

55 10. A train coupler system comprising coupler operating mechanism for controlling the relation of the couplers between adjoining cars of the train, an electric circuit provided with remote switch control connections and electromagnetic means for operating the coupler mechanism of each of said cars, and remote control means including fluid-pressure operated elements adapted to be actuated from the air brake line of the train for successively breaking the coupler control circuit in the several cars from said remote control point to a given car of the train.

11. A train coupler system comprising coupler operating mechanisms for controlling the relation of the couplers between adjoining cars of the train, an electric circuit provided with remote switch control connections and branch circuits on each car having electromagnetic means for operating the coupler mechanism thereof, a switch in each branch circuit for opening and closing the same, remote control means opera-

tive for successively closing the said branch circuit switches throughout the train, and a remote control connection including fluid-pressure operated elements adapted to be actuated from the air brake line of the train for effecting the successive opening of said switches from said remote control point to a given car of the train.

12. A train coupler system comprising coupler operating mechanisms for controlling the relation of the couplers between adjoining cars of the train, and including fluid-pressure operated elements adapted to be actuated from the air brake line of the train, an electric circuit provided with remote switch control connections and electromagnetic means for operating said fluid-pressure elements in the coupler mechanism of each of said cars, and remote control means for selectively confining the operation of said first circuit to the coupler mechanism of a single car of the train, said first circuit including means for selectively actuating the coupler connection at either end of each car of the train.

13. A train coupler system comprising a signal and indicator circuit including separable circuit-connecting elements in engagement at the coupled ends of adjoining cars, a car coupler control circuit provided with remote switch control connections and separable circuit-connecting elements in engagement at said coupled ends of the cars, and signaling means operative to indicate progressively in either direction the order of the cars affected by the operations of said second circuit and responding simultaneously to said operations to successively indicate the cars affected thereby.

14. A train coupler system comprising a signal and indicator circuit including separable circuit-connecting elements in engagement at the coupled ends of adjoining cars, a car coupler control circuit provided with remote switch control connections and separable circuit-connecting elements in engagement at said coupled ends of the cars, and signaling means operative to indicate the order of the cars affected by the operations of said second circuit and responding simultaneously to said operations to successively indicate the cars affected thereby and including an auxiliary signaling element operating successively to indicate each coupled relationship of adjoining cars in a predetermined end-to-end relation.

15. A train coupler system comprising a signal and indicator circuit including separable circuit-connecting elements in engagement at the coupled ends of adjoining cars, a car coupler control circuit provided with remote switch control connections and separable circuit connecting elements in engagement at said coupled ends of the cars, both sets of said connecting elements being arranged to permit contacting engagement thereof in either of the two opposite end-to-end relations of the several cars, and a signal device automatically responsive to the operative engagement of said elements in said coupler control circuit for indicating either one of the relative end-to-end positions of the cars.

16. A train coupler system comprising coupler operating mechanisms for controlling the relation of the couplers between adjoining cars of the train, an electric circuit provided with remote switch control connections and electromagnetic means for operating the coupler mechanism of each of said cars, remote control means for successively closing the coupler control circuit in the several cars from said remote control point to a given car of the train, and an indicating circuit responsive to said control operations for succes-

sively indicating the positions of the cars affected by said operations.

17. A train coupler system comprising coupler operating mechanisms for controlling the relation of the couplers between adjoining cars of the train, an electric circuit provided with remote switch control connections and electromagnetic means for operating the coupler mechanism of each of said cars, remote control means for successively breaking the coupler control circuit in the several cars from said remote control point to a given car of the train, and an indicating circuit responsive to said control operations for successively indicating the positions of the cars affected by said operations.

18. A train coupler system comprising coupler operating mechanisms for controlling the relation of the couplers between adjoining cars of the train, an electric circuit provided with remote switch control connections and electromagnetic means for operating the coupler mechanism of each of said cars, and remote control means operative either to open or close the coupler control circuit in the several cars in successive order from said remote control point to a given car in the train.

19. A train coupler system comprising coupler operating mechanisms for controlling the rela-

tion of the couplers between adjoining cars of the train, an electric circuit provided with remote switch control connections and electromagnetic means for operating the coupler mechanism of each of said cars, remote control means operative either to open or close the coupler control circuit in the several cars in successive order from said remote control point to a given car in the train, and an indicating circuit responsive to said control operations for successively indicating the 10 positions of the cars affected by said operations.

20. A train coupler system comprising a signal and indicator circuit including separable circuit-connecting elements in engagement at the coupled ends of adjoining cars, a car coupler control circuit provided with remote switch control connections and separable circuit connecting elements in engagement at said coupled ends of the cars, both sets of said connecting elements being arranged to permit contacting engagement there- 15 of in either end-to-end relation of the several cars, and means responsive to the operations of said second circuit for actuating the first circuit to indicate the positions of the cars affected by said operations and including a signal device indicat- 20 ing one of the relative end-to-end positions of the cars.

OTTO E. DE HAVEN.
